ART OF CRACKING HYDROCARBONS.

Application filed November 20, 1924. Serial No. 750,896.

This invention relates to an improved method and apparatus for cracking heavier hydrocarbon oils for the production of lighter and lower boiling hydrocarbon oils, such as gasoline or pressure distillate. More particularly, this invention relates to improvements in methods of cracking hydrocarbon oils in which the oil is circulated from and to a bulk supply tank through a heater, and to an improved arrangement and construction of apparatus for carrying out cracking processes of this character.

In circulatory pressure stills where the oil is heated in a tubular heater and circulated from and to a bulk supply tank, the heat is applied to the oil while it is being circulated through the heater so that the oil entering the bulk supply tank from the heater is at a somewhat higher temperature than that of the oil into which it is introduced in the bulk supply tank. Cracking may take place to a greater or less extent throughout the body of oil in the bulk supply tank. The separation of cracked vapors take place in the bulk supply tank and these vapors are withdrawn usually through a reflux tower to a condenser. Where active circulation of the oil through the heater from and to the bulk supply tank is effected, the circulating stream of oil maintains the entire body of oil in the bulk supply tank in agitation to a greater or less extent, with resulting turbulence which interferes with the separations of cracked vapors with the result that the oil withdrawn from the bulk supply tank and recirculated through the heater may still contain vaporizable constituents which has not had an opportunity of separating in the bulk supply tank before the oil is recirculated.

According to the present invention, this turbulence or eddying of the oil in the bulk supply tank, due to the rapid inflow of hot oil and vapors from the heater and the rapid circulation of the oil, is prevented or greatly reduced, so that the separation of cracked vapors is facilitated, and so that the recirculation of cracked vapors with the oil from the bulk supply tank through and to the heater is prevented or greatly reduced.

The invention includes both an improved arrangement and construction of apparatus for cracking oils and also an improved

method of cracking oils in such apparatus. In the apparatus of the present invention 65 one or more baffles, or their equivalents, are arranged in the bulk supply tank below the point at which the return circulating line or lines from the heater discharge therein, and above the outlet from the bulk supply tank to 60 the heater, so that stratification of the oil in the bulk supply tank is promoted. As a result of this baffle arrangement and of the resulting stratification, the separation of cracked vapors from the upper layers of the 65 oil in the bulk supply tank is facilitated, and so that the oil which goes down into the lower part of the bulk supply tank beneath the baffles is relatively free from vaporizable cracked constituents, and so that the oil 70 which is withdrawn from the bulk supply tank and circulated through the heater is also relatively free from such vaporizable cracked constituents at the time it enters the heater. 75

In the improved process of the invention, the oil is circulated from the bulk supply tank through the heater and back to the bulk supply tank and is caused to undergo stratification because of the baffle arrangement in the bulk supply tank and the cracked vapors are for the most part if not entirely removed from the upper layers or strata of the oil in the bulk supply tank and so that such eddying or turbulence as exists is largely confined to the upper layers above the baffles into which the return line or lines from the heater discharge. During this improved method of circulation, the active vaporizing and the eddying or turbulence of 80 the oil are largely if not entirely confined to these upper layers or strata above the baffles while the oil which flows downwardly around or past the baffles to the lower part of the bulk supply tank is relatively free 85 from vaporizable constituents and is relatively quiescent so that a better opportunity is provided for the separation of further amounts of vaporizable constituents therefrom, because of the greater quiescence, and so that a better opportunity is also provided for the separation out in the bottom of the bulk supply tank, of particles carried in suspension in the oil, and which might otherwise, because of the eddying or turbulence of the entire body of oil in the bulk 100 105

supply tank, be carried in suspension again through the heater.

In the apparatus of the invention, the baffles or their equivalents are arranged to permit free circulation of the unvaporized oil in a generally downward direction through the bulk supply tank from the upper and more turbulent layers to the lower and more quiescent layers, while largely confining the liberation of vapors to the upper part or layers of the charge in the bulk supply tank. The baffles do not interfere with the circulation of the oil from the bulk supply tank to the heater and back to the bulk supply tank, but their main function is to control and regulate to a greater or less extent the nature and character of the circulation within the bulk supply tank itself and to cause stratification so that the liberation of vapors is largely confined to the upper layers of oil in the bulk supply tank. The turbulence or eddying due to the introduction of the hot oil and vapors from the heater is also largely confined to the upper portion of the charge in the bulk supply tank, while the unvaporized oil, relatively free from vapors or constituents tending to vaporize in the bulk supply tank, settles or flows to the lower part of the bulk supply tank where it is relatively quiescent and free from disturbing eddying and turbulence. The cross-sectional area of the bulk supply tank being much larger than that of the circulating lines to and from the heater, the rate of flow downwardly in the bulk supply tank from the point of reintroduction of oil from the heater to the point of withdrawal of oil flowing to the heater is relatively slow as compared with the rate of circulation through the heater. Because of this relatively slow circulating of the charge as a whole through the bulk supply tank, and because of the stratification in the charge brought about by the baffles or their equivalents, the bulk supply tank charge can be considered as having a generally downward flow around the baffles and at a greatly reduced rate, and the portion of the charge which has flowed downwardly around and beneath the baffles is in the relatively quiescent state above referred to. In this way a more complete separation of the vapors and light cracked constituents is effected in the bulk supply tank and the oil recirculated to the heater is practically free from such constituents.

The present invention accordingly prevents or inhibits very largely the eddying or turbulence which might otherwise prevent effective separation of cracked vapors and cause them to be carried again through the heater before sufficient opportunity for their separation has been provided.

The invention is of more or less general

application to circulatory pressure stills in which there is circulation from the bulk supply tank to and through a tubular heater and back to the bulk supply tank. Circulatory pressure stills of this kind can be modified in their construction by the provision of baffles suitably arranged in the bulk supply tank to prevent objectionable eddying or turbulence and to bring about the desired stratification so that the lower levels or layers of oil in the bulk supply tank, from which the oil is withdrawn for recirculation through the heater, are relatively quiescent. A still of this general construction is described and illustrated in U. S. Letters Patent No. 1,285,200, granted to the Sinclair Refining Company, November 19, 1918, on the application of Edward W. Isom, and the present invention will be more particularly described in connection therewith.

In carrying out the invention in a circulatory pressure still provided with a reflux tower, the reflux may be returned and introduced for example into the stream of oil circulating from the bulk supply tank to the heater. Where fresh feed is introduced during the progress of the operation, it may, in a similar manner, be introduced into the circulating still charge at a place where the charge is relatively free from vapors and light cracked constituents, and initially circulated to the heater without being circulated through the turbulent vaporizing zone in the bulk supply tank. Where fresh feed is employed to promote or assist the refluxing operation by introduction into direct contact with the vapors escaping from the bulk supply tank, the reflux and admixed feed may be returned together to a cooler part of the still charge. Owing to the fact that the hottest oil from the heater enters the bulk supply tank above the baffles and admixes with the oil in the upper portion of the bulk supply tank, it will be evident that the oil stratifying and circulating slowly to the lower part of the bulk supply tank will be relatively cooler than that in the upper portion. When the reflux or the feed, or the admixed reflux and feed, is introduced into the lower portion of the still, it will thus come in contact with oil at a somewhat lower temperature than that in the upper portion of the bulk supply tank; while if the reflux, or feed, or admixed reflux and feed, is introduced into the circulating line between the bulk supply and the heater, it will admix with oil which is also at a lower temperature and which is relatively free from vaporizable cracked constituents.

The present invention is of special value and application in connection with continuous or semi-continuous cracking processes in which fresh oil is introduced into the still charge,

and in which tar is withdrawn from the still charge, during the progress of the cracking operation. In carrying out the present invention in connection with such methods of operation, the tar is withdrawn from the lower and cooler part of the still charge. The tar, for example, may be withdrawn from a lower stratum of the oil in the bulk supply tank which is relatively free from vapors and light cracked constituents, and which is relatively free from turbulence. Stratification of the charge of oil in the bulk supply tank promotes the separation of the tar-laden part of the still charge and assists in concentrating the tarry constituents in the stratum from which tar is drawn off. At the same time, by confining vaporization and turbulence to the upper part of the charge in the bulk supply tank, and by withdrawing the tar from the lower, quiet and cooler part of the charge therein which is relatively free from vapors and light cracked constituents, and withdrawal of vapors or light cracked constituents with the tar is prevented or greatly reduced.

The invention will be further described in connection with the accompanying drawing illustrating an embodiment of the apparatus of the invention adapted for carrying out the process of the invention, but it is intended and will be understood that the invention is illustrated thereby and not limited thereto.

In the accompanying drawing,

Fig. 1 represents, diagrammatically and partly in section and partly in elevation, a pressure still system embodying the invention and adapted for carrying out the invention.

Fig. 2 is a section on line 2-2 of Fig. 1, and

Fig. 3 is a view similar to Fig. 2, illustrating a different arrangement of the bulk supply tank of the pressure still.

The pressure still illustrated in the drawing comprises a bulk supply tank 1, a heater consisting of a bank of tubes 2 vertically arranged in the heating flue of the furnace 3, a circulating pump 4, and circulating lines 5, 6 and 7 connecting, in order, the bulk supply tank, the circulating pump, the lower end of the heating tubes, the upper end of the heating tubes and the bulk supply tank.

Arranged above the bulk supply tank is a reflux tower 8 having a series of baffles therein. The vapors liberated in the bulk supply tank escape to the lower end of the reflux tower through the vapor line 9. A return reflux line 10 is provided for returning reflux from the bottom of the tower to the pressure still. The vapors from the reflux tower escape through the vapor line 11 to the condenser 12 which discharges into the receiver 13 from which the condensed distillate is withdrawn through the outlet

14 and from which the uncondensed vapors and gases are withdrawn through the outlet 15.

A feed line 16 is provided for introducing fresh charging stock into the upper end of the reflux tower in direct contact with the vapors therein, and connection 17 is arranged for introducing cool oil into the circulating stream of oil through the bearings of the circulating pump. A tar drawoff for withdrawing tar during the progress of the cracking operation is shown at 18, and a connection 19 is provided for pumping out and initially charging the still.

The pressure may be reduced and regulated by the regulating valve 20 arranged between the reflux tower and the condenser, or the condenser may be operated at substantially the pressure prevailing in the still and the pressure may be reduced and regulated by suitable regulating valve arranged beyond the receiver.

In the bulk supply tank of the pressure still illustrated, oil is withdrawn through the drop leg 5 and is circulated upwardly through the heater and back to the bulk supply tank through a pair of connections 7. The drop leg 5 opens into the lower part of the charge in the bulk supply tank and is arranged to withdraw oil from the lower and cooler part of the charge therein. The hot oil and vapors from the heater are introduced into the upper part of the charge in the bulk supply tank.

Arranged below the inlet connections 7 in the bulk supply tank, and above the outlet to the drop leg 5, are a series of horizontal baffles 21, shown as three in number, extending throughout the length of the bulk supply tank. These baffles, staggered as shown, tend to divide the charge in the bulk supply tank into an upper stratum A and a lower stratum B while nevertheless permitting a free circulation of unvaporized oil from the upper stratum to the lower stratum.

The hot vapor-laden and vaporizing oil from the heater is introduced into the charge in the bulk supply tank above the baffles and the baffles tend to confine the turbulence and eddying due to the introduction of the hot oil and vapors to the upper part or upper stratum of the oil in the bulk supply tank. The baffles also assist in confining the liberation of vapors to that part of the charge above the baffles, and in confining the hot vapor-laden oil from the heater to the upper part of the charge where vapors more readily escape, and assist in promoting a more complete liberation of the vaporizable constituents in the hot oil from the heater.

The baffles also tend to maintain a relatively quiet and cooler zone in the lower part of the charge in the bulk supply tank from which the unvaporized oil is recirculated through the heater. The oil in this

lower and cooler stratum is relatively free from vapors and light cracked constituents. Reflux from the reflux tower is returned through the reflux return line 10 to the upper end of the drop leg 5 where it is drawn by the suction of the circulating pump downwardly through the drop leg in admixture with cooler oil from the lower part of the bulk supply tank and circulated back to the bulk supply tank through the heater. The reflux is thus returned to the heater in admixture with unvaporized oil from the bulk supply tank without passing through the turbulent zone in the upper part of the bulk supply tank in which vapors are being liberated from the oil from the heater and where it would otherwise be subjected to a higher temperature, by contact with the hot oil fresh from the heater, with resulting vaporization and escape of vaporized constituents without being resubjected to the cracking temperature in the heater. Fresh charging stock introduced into the reflux tower, after passing through the tower, is introduced in admixture with the reflux into the stream of cooler oil circulating from the bulk supply tank to the heater.

The tar drawoff 18 is provided for withdrawing tar during the progress of the cracking operation, and is arranged to withdraw tar from the lower part of the charge in the bulk supply tank or lower stratum B. The tarry constituents do not tend to vaporize, and, due to the provision of the baffles, tend to collect with the unvaporized oil in the lower part of the charge below the baffles. This lower zone is relatively quiet and the oil therein is not continually intermixed with hot oil fresh from the heater so that an opportunity is provided for the escape of such readily vaporizable constituents as are carried below the baffles and so that the oil below the baffles becomes substantially free from vapors and like cracked constituents. The baffles also tend to increase the concentration of the tarry constituents in the lower stratum in the bulk supply tank by promoting a more complete vaporization of the light constituents.

The function of the baffles is to promote a stratification of the still charge in the bulk supply tank and to divide it into an upper zone, to which active vaporization and turbulence due to the introduction of hot oil and vapors from the heater is confined, and a lower cooler zone to which the unvaporized oil is free to circulate from the upper zone. The baffles may be constructed of metal or other suitable material free from catalytic effect upon the still charge.

In operation, the still is charged, with gas oil for example, and brought to cracking conditions of temperature and pressure, and distillation is begun. With ordinary

gas oil charging stocks, pressures, for example, in the neighborhood of 90 to 125 lbs. per square inch may be employed; or, with lighter charging stocks, such as a kerosene character stock, for example, pressures up to as high as 300 lbs. per square inch or higher may be employed. Fresh feed is introduced through the reflux tower into direct contact with the vapors escaping through the reflux tower from the bulk supply tank, and the resulting admixed feed and reflux is introduced into the circulating stream of oil flowing from the lower part of the bulk supply tank to the heater. The circulating oil is passed upwardly through the heating tubes from which the hot oil and vapors are discharged into the bulk supply tank above the baffles. The vapors are for the most part liberated from the hot oil in the upper part of the bulk supply tank and escape through the reflux tower, while the unvaporized oil and tarry constituents flow to the quiet and cooler zone in the lower part of the bulk supply tank below the baffles.

In carrying out a continuous cracking operation in the still illustrated, tar is withdrawn from the lower part of the charge in the bulk supply tank through the tar drawoff 18 in amount sufficient to maintain the concentration of tarry constituents in the still charge below an objectionable point, and sufficient fresh charging stock is introduced into the still to maintain the charge therein.

In the different form of apparatus illustrated in Fig. 3, a screen 22 is arranged in the bulk supply tank below the circulating connections from the heater and above the outlet to the circulating connection to the heater. A screen, arranged as illustrated, is useful in inhibiting turbulence in the lower part of the still charge and in confining the main liberation of vapors to the upper part of the still charge. A screen, however, is not as advantageous as baffles of the type illustrated, since there is apparently a greater tendency for circulation of the hot oil and vapors from the heater therethrough before vaporization is substantially completed, so that stratification is not promoted as effectively as with a baffle or baffles. If the concentration of tarry constituents in the still charge exceeds the saturation point and precipitation begins, a screen also tends to choke or clog with precipitated carbon and tarry matter.

One of the important advantages of the present invention is that it substantially prevents or materially reduces over-cracking of constituents desirable in the pressure distillate. Overcracking tends to cause objectionable unsaturation and likewise results in the conversion of increased amounts of the charging stock into incondensable gases. Where the agitation due to the in-

duction of the hot oil and vapors circulating from the heater into the bulk supply tank is unrestricted, the consequent turbulence tends to carry some vapors and light cracked constituents again through the heater with the circulating oil before they can be liberated in the bulk supply tank, resulting in further subjection of these vapors and light cracked constituents to the cracking temperature in the heater with consequent overcracking. By causing a stratification of the still charge in the bulk supply tank, and by confining the liberation of vapors and the turbulence due to the introduction of hot oil and vapors from the heater largely to the upper stratum, a more complete separation of the vapors and light cracked constituents is effected in the bulk supply tank, and objectionable overcracking of such constituents as might otherwise be carried along with the circulating oil is avoided.

The invention has been particularly described in connection with the construction and operation of a circulatory still in which the circulation was mechanically promoted by a pump. The invention is also useful in connection with circulatory cracking stills in which circulation is maintained without mechanical circulating means, although to a lesser degree. Where a circulating pump is employed, comparatively rapid circulation is effected and the turbulence in the bulk supply tank and the tendency to carry vapors and light cracked constituents with the circulating oil before they can be liberated is relatively increased. Where a circulating pump is not employed, this tendency is not as marked, but the operation of such circulatory pressure cracking stills may nevertheless be improved by causing a stratification of the charge in the bulk supply tank.

It will thus be seen that the invention provides for improvements in the constructions and in the operation of circulatory pressure stills, and particularly stills in which a large charge of oil is maintained in a bulk supply tank and circulated therethrough through a tubular heater and back to the bulk supply tank. It will also be seen that the invention is of more or less general application to charging stocks of different kinds and to pressure still operations carried out at different temperatures and pressures, depending upon the charging stock which is used for charging the pressure still. It will also be evident that baffling arrangements of various kinds can be used to bring about the desired stratification and to prevent the undesired turbulence and eddying obtained in pressure stills in which there is no impediment to the turbulence and eddying in the bulk supply tank. It will also be evident that the pressure still

embodying the invention and the process carried out therein are capable of modification in various ways, such as the reintroduction of reflux, the withdrawal of tar, the introduction of additional feed, and the carrying out of the pressure distillation as a continuous operation over long periods of time, the improvement in the operation of the cracking process being favorable to such continued and prolonged operation.

It will also be evident that variations and modifications can be made in the construction of the pressure still and in the method of operation without departing from the spirit and scope of the invention.

We claim:

1. A method of cracking hydrocarbon oils, which comprises circulating the oil from and to a bulk supply tank through a heater maintaining a large body of oil in the bulk supply tank, heating the oil to a cracking temperature in the heater, causing a stratification of the oil in the bulk supply tank by obstructing the free flow of oil downwardly in said body and thereby confining the turbulence due to the introduction of the oil from the heater into the bulk supply tank to the upper stratum, and withdrawing oil from the lower stratum for recirculation through the heater.

2. A method of cracking hydrocarbon oils, which comprises mechanically circulating the oil from and to a bulk supply tank through a heater maintaining a large body of oil in the bulk supply tank, heating the oil to a cracking temperature in the heater, causing a stratification of the oil in the bulk supply tank by obstructing the free flow of oil downwardly in said body and thereby confining the turbulence due to the introduction of the oil from the heater into the bulk supply tank to the upper stratum, and withdrawing oil from the lower stratum for recirculation through the heater.

3. A method of cracking hydrocarbon oils, which comprises circulating the oil from and to a bulk supply tank through a heater maintaining a large body of oil in the bulk supply tank, heating the oil to a cracking temperature in the heater, causing a stratification of the oil in the bulk supply tank by obstructing the free flow of oil downwardly in said body and thereby confining the turbulence due to the introduction of the oil from the heater into the bulk supply tank to the upper stratum, subjecting the vapors escaping from the bulk supply tank to a refluxing operation, returning reflux to the oil in the lower stratum, and withdrawing oil from the lower stratum for recirculation through the heater.

4. A method of cracking hydrocarbon oils, which comprises circulating the oil from and to a bulk supply tank through a heater maintaining a large body of oil in the bulk

- supply tank, heating the oil to a cracking temperature in the heater, causing a stratification of the oil in the bulk supply tank by obstructing the free flow of oil downwardly in said body and thereby confining the turbulence due to the introduction of the oil from the heater into the bulk supply tank to the upper stratum, withdrawing oil from the lower stratum for recirculation through the heater, subjecting the vapors escaping from the bulk supply tank to a refluxing operation, and recirculating the reflux from the refluxing operation through the heater with the oil from the lower stratum.
5. A method of cracking hydrocarbon oils, which comprises pumping the oil from a bulk supply tank through a heater and back to the bulk supply tank, heating the oil to a cracking temperature in the heater maintaining a large body of oil in the bulk supply tank, causing a stratification of the oil in the bulk supply tank by obstructing the free flow of oil downwardly in said body and thereby confining the turbulence due to the introduction of the oil from the heater into the bulk supply tank to the upper stratum, subjecting the vapors escaping from the bulk supply tank to a refluxing operation, and pumping the reflux from the refluxing operation with oil withdrawn from the lower stratum through the heater.
6. A method of cracking hydrocarbon oils, which comprises circulating the oil from and to a bulk supply tank through a heater maintaining a large body of oil in the bulk supply tank, heating the oil to a cracking temperature in the heater, causing a stratification of the oil in the bulk supply tank by obstructing the free flow of oil downwardly in said body and thereby confining the turbulence due to the introduction of the oil from the heater into the bulk supply tank to the upper stratum, subjecting the vapors escaping from the bulk supply tank to a refluxing operation in direct contact with fresh charging stock, and circulating the reflux and admixed charging stock through the heater with oil withdrawn from the lower stratum.
7. A method of cracking hydrocarbon oils, which comprises circulating the oil from and to a bulk supply tank through a heater maintaining a large body of oil in the bulk supply tank, heating the oil to a cracking temperature in the heater, causing a stratification of the oil in the bulk supply tank by obstructing the free flow of oil downwardly in said body and thereby confining the turbulence due to the introduction of the oil from the heater into the bulk supply tank to the upper stratum, withdrawing tar from the lower stratum, and recirculating oil withdrawn from the lower stratum through the heater.
8. A method of cracking hydrocarbon oils, which comprises circulating the oil from and to a bulk supply tank through a heater maintaining a large body of oil in the bulk supply tank, heating the oil to a cracking temperature in the heater, causing a stratification of the oil in the bulk supply tank by obstructing the free flow of oil downwardly in said body and thereby confining the turbulence due to the introduction of oil from the heater into the bulk supply tank to the upper stratum while permitting circulation of unvaporized constituents to the lower stratum, and withdrawing oil from the lower stratum for recirculation through the heater.
9. A method of cracking hydrocarbon oils, which comprises circulating the oil from and to a bulk supply tank through a heater maintaining a large body of oil in the bulk supply tank, heating the oil to a cracking temperature in the heater, causing a stratification of the oil in the bulk supply tank by obstructing the free flow of oil downwardly in said body and thereby confining the turbulence due to the introduction of oil from the heater into the bulk supply tank to the upper stratum while permitting circulation of unvaporized oil and associated tarry constituents to the lower stratum, withdrawing tar from the lower stratum, and recirculating oil withdrawn from the lower stratum through the heater.
10. A method of cracking hydrocarbon oils, which comprises circulating the oil from and to a bulk supply tank through a heater maintaining a large body of oil in the bulk supply tank, heating the oil to a cracking temperature in the heater, causing a stratification of the oil in the bulk supply tank by obstructing the free flow of oil downwardly in said body and thereby confining the turbulence due to the introduction of the oil from the heater into the bulk supply tank to the upper stratum, withdrawing oil from the lower stratum for recirculation through the heater, and withdrawing tar from the operation from the lower stratum and supplying fresh charging stock.
11. An apparatus for distilling hydrocarbon oils under pressure, comprising a bulk supply tank and a heater, circulating connections from the lower part of the bulk supply tank to the heater and from the heater to a higher part of the bulk supply tank, and baffle means for confining turbulence to the upper stratum of oil in the bulk supply tank arranged in the bulk supply tank between the circulating connections from the heater and the circulating connections to the heater below the normal liquid level therein.
12. An apparatus for distilling hydrocarbon oils under pressure, comprising a bulk supply tank and a heater, circulating con-

- nections including a pump from the lower part of the bulk supply tank to the heater and from the heater to a higher part of the bulk supply tank, and baffle means for confining turbulence to the upper stratum of oil in the bulk supply tank arranged in the bulk supply tank between the circulating connections from the heater and the circulating connections to the heater below the normal liquid level therein.
13. An apparatus for distilling hydrocarbon oils under pressure, comprising a bulk supply tank and a heater, circulating connections from the lower part of the bulk supply tank to the heater and from the heater to a higher part of the bulk supply tank, baffle means for confining turbulence to the upper stratum of oil in the bulk supply tank arranged in the bulk supply tank between the circulating connections from the heater and the circulating connections to the heater below the normal liquid level therein, a reflux tower communicating with the vapor space in the bulk supply tank and connections for returning reflux therefrom to a point between the lower side of the baffle means and the heater.
14. An apparatus for distilling hydrocarbon oils under pressure, comprising a bulk supply tank and a heater, circulating connections from the lower part of the bulk supply tank to the heater and from the heater to a higher part of the bulk supply tank, baffle means for confining turbulence to the upper stratum of oil in the bulk supply tank arranged in the bulk supply tank between the circulating connections from the heater and the circulating connections to the heater below the normal liquid level therein, a reflux tower communicating with the vapor space in the bulk supply tank, means for introducing fresh charging stock directly into the reflux tower, and connections for returning reflux and admixed charging stock therefrom to a point between the lower side of the baffle means and the heater.
15. An apparatus for distilling hydrocarbon oils under pressure, comprising a bulk supply tank and a heater, circulating connections from the lower part of the bulk supply tank to the heater and from the heater to a higher part of the bulk supply tank, baffle means for confining turbulence to the upper stratum of oil in the bulk supply tank arranged in the bulk supply tank between the circulating connections from the heater and the circulating connections to the heater below the normal liquid level therein, and a connection for withdrawing tar from the bulk supply tank below said baffle means.
16. An apparatus for distilling hydrocarbon oils under pressure, comprising a bulk supply tank and a heater, circulating connections from the lower part of the bulk supply tank to the heater and from the heater to a higher part of the bulk supply tank, and means arranged in the bulk supply tank between the circulating connections from the heater and the circulating connections to the heater below the normal liquid level therein for causing a stratification of oil in the bulk supply tank and for confining turbulence to the upper part of the bulk supply tank.
17. An apparatus for distilling hydrocarbon oils under pressure, comprising a bulk supply tank and a heater, circulating connections including a pump from the lower part of the bulk supply tank to the heater and from the heater to a higher part of the bulk supply tank, and means arranged in the bulk supply tank between the circulating connections from the heater and the circulating connections to the heater below the normal liquid level therein for causing a stratification of oil in the bulk supply tank and for confining turbulence to the upper part of the bulk supply tank.
18. An apparatus for distilling hydrocarbon oils under pressure, comprising a bulk supply tank and a heater, circulating connections from the lower part of the bulk supply tank to the heater and from the heater to a higher part of the bulk supply tank, and means arranged in the bulk supply tank between the circulating connections from the heater and the circulating connections to the heater below the normal liquid level therein for preventing turbulence in the lower part of the bulk supply tank.

In testimony whereof we affix our signatures.

1,592,489.—*Eugene C. Herhel*, Chicago, Ill., and *Edward W. Isom*, Locust Valley, N. Y.
ART OF CRACKING HYDROCARBONS. Patent dated July 13, 1926. Disclaimer filed November 23, 1928, by the assignee, *Sinclair Refining Company*.

Hereby enters this disclaimer to the method of said claims 1, 2, 7, 8, 9, and 10 except as applied to the separation from oil recirculated from the bulk supply tank through the heater of constituents vaporizable under the conditions of temperature and pressure prevailing in the bulk supply tank, and to the apparatus of said claims 11, 15, 16, and 18 except such apparatus in which the hot oil products from the heater are discharged together through the same circulating connections from the heater to the bulk supply tank.

[Official Gazette December 11, 1928.]

DISCLAIMER.
